CLAIM

The ornamental design for a golf tool for cleaning club face grooves, tightening spikes and repairing divots, as shown and described.

DESCRIPTION

FIG. 1 is a front, left perspective view of a golf tool for cleaning club face grooves, tightening spikes and repairing divots showing my new design;

FIG. 2 is a front elevation of FIG. 1, the rear being a mirror image thereof;

FIG. 3 is a side elevation taken from the right of FIG. 1;

FIG. 4 shows an end view taken along the right side of FIG. 3; and,

FIG. 5 shows an end view taken along the left side of FIG. 3.
